CLAIM

The ornamental design for an actuator assembly for a valved catheter, as shown and described.

DESCRIPTION

FIG. 1 is a perspective view of an actuator assembly for a valved catheter, showing our new design;

FIG. 2 is a perspective view of the same design from a different viewing angle;

FIG. 3 is a top plan view thereof;

FIG. 4 is a left side elevation view thereof;

FIG. 5 is a right side elevation view thereof;

FIG. 6 is a rear elevation view thereof; and,

FIG. 7 is a front elevation view thereof.
